UNITED STATES PATENT OFFICE.

CHARLES SPIRO, OF NEW YORK, N. Y.

TABULATING MECHANISM.

987,766.

Specification of Letters Patent. Patented Mar. 28, 1911.

Application filed August 15, 1910. Serial No. 577,182.

To all whom it may concern:

Be it known that I, CHARLES SPIRO, a citizen of the United States, residing at New York, county of New York, State of New York, have invented certain new and useful Improvements in Tabulating Mechanism, of which the following is a specification, reference being had therein to the accompanying drawing.

- 10 The invention disclosed in this application relates broadly to typewriting machines and specifically to tabulating mechanism for determining relative lateral positions of the platen carriage.
- 15 The principal object of this invention is to construct a tabulating mechanism for typewriting machines wherein the printing mechanisms are locked in inoperative position when a tabulating key is depressed to cause 20 the carriage to jump to a predetermined position.

Another object of this invention is to construct a tabulating mechanism wherein the tabulator key is locked down after having 25 been depressed to actuate the tabulating devices, until the platen carriage has reached a predetermined position.

Another object of this invention is to construct a tabulating mechanism in which the 30 platen carriage is disconnected from the control of the escapement devices when a tabulating key is depressed, and is automatically thrown under control of the escapement mechanisms when the carriage has reached a 35 predetermined point in its travel.

Another object of this invention is to construct a tabulating device in which a brake mechanism is automatically thrown into operation by the actuator stop carrier to control 40 the force of the driving spring when a tabulating stop is positioned.

Another object of this invention is to construct a tabulating mechanism wherein the tabulating stop is locked in position when a 45 tabulating key is depressed, and is automatically unlocked by means of a cam actuating stop before the adjustable stop and the tabulating stop come in contact.

Another object of this invention is to construct 50 an adjustable stop member for tabulating mechanism, in horse-shoe form, one portion of said adjustable stop being formed with a cam actuating face and another portion of said stop being formed with a tabulating face.

Another object of this invention is to con-

struct a removable index scale adapted to coöperate with tabulating keys of the typewriting machine.

Still other and further objects of this invention will in part be obvious and will in part be pointed out in the specification hereinafter following by reference to the accompanying drawings in which like numerals are used to indicate like parts throughout the several figures, and the scope of the invention will be indicated by the appended claims.

Figure 1 is a rear view of a typewriting machine showing the position of the tabulating mechanism. Fig. 2 is a top view of the typewriting machine illustrating the tabulating rack and adjustable stop mounted thereupon. Fig. 3 is a sectional view showing the arrangement of the tabulating key levers. Fig. 4 is a view showing the tabulator stop. Fig. 5 is a plan view of one tabulator stop and actuating mechanism. Fig. 6 is a view showing one tabulator stop in end elevation. Fig. 7 is a sectional detail view of the tabulator stop and the adjustable cam stop. Fig. 8 is a plan view showing a detail of the releasing mechanism. Fig. 9 is an elevational view showing a detail of the releasing mechanism. Fig. 10 is a plan view showing a detail of the braking mechanism. Fig. 11 is an elevational view showing a detail of the braking mechanism. Fig. 12 is a detail of the holding dog for the escapement. Fig. 13 is a detail of the escapement dog. Fig. 14 is a view showing the adjustable tabulator scale in front elevation. Fig. 15 is a view showing the adjustable tabulator scale in end elevation. Fig. 16 is a view showing the adjustable tabulator scale in plan. Fig. 17 is an elevational view showing a modification of the tabulating mechanism adapted for column stop work. Fig. 18 is a view showing a modification of the tabulating mechanism adapted for column stop work in plan. Figs. 19 and 20 are details of the tabulating key. Figs. 21 and 22 are details of the adjustable tabulator stop. Fig. 23 is a view showing column stop devices in rear elevation. Fig. 24 is a detail plan view of the adjustable stop and the column stop. Fig. 25 is a view showing the column stop carrier in side elevation. Fig. 26 is a view showing the column stop carrier in edge elevation. Fig. 27 is a plan view of the bracket member. Fig. 28 is an elevational

view of the bracket member. Fig. 29 is an end elevational view of the bracket member.

Referring particularly to Figs. 1, 2 and 3, wherein are illustrated many parts of the typewriting machine that do not specifically coöperate with the tabulating mechanism, these parts of the typewriting machine which do not specifically coöperate with the tabulating mechanism are covered by applications for patent which are co-pending with this application, and these particular parts will be referred to generally in the specification hereinafter.

Referring more particularly to Figs. 1, 2 and 3 of this application, the main frame is comprised of side members 1, which are connected at their rear portion by means of a rear bar 2, and at their front portion by means of a front bar (not illustrated in the drawings). Supporting posts 4 and 5, are formed integral with the side members 1, and carry upon their upper ends a top plate 6, which is attached to the supporting posts 4 and 5, by means of a screw 7, or any well-known device for interlocking metallic parts. Key levers 8, are pivotally mounted in the machine frame and terminate at their forward ends in key caps 9. A universal bar 10, is mounted in such relation as to be adapted to be actuated each time one of the key levers 8 is depressed. A platen carriage mechanism 11, is mounted for reciprocation upon the top plate 6, and is adapted to carry a cylindrical platen 12, which is fitted with line spacing mechanism 14. Ribbon spools 15 and 16 are mounted for rotation upon the top plate 6, and are adapted to carry a ribbon 17, which passes through a ribbon vibrator 18, which is located at the printing point. A back spacing dog 19, is mounted upon the top plate 6, and is adapted to coöperate with a back spacing rack 20, which is carried upon the platen carriage 11.

Referring more particularly to Figs. 2 to 16 inclusive, tabulating keys 21, are mounted upon a pivotal support 22, which is mounted in the machine frame, and are connected at their rear end with vertical tabulator stop carriers 24, that are provided with slots 25, which coöperate with a stud bolt 26, in such manner as to guide the stop carriers 24 when they are reciprocated by means of the tabulating keys 21. Small coiled springs 23, are attached to the tabulating keys 21, in such manner as to cause the parts to resume normal position when pressure is released from the tabulating keys. The tabulator stop carriers 24, are provided with contact shelves 27, which are adapted to lie beneath a releasing bail 28, and a braking bail 29, both of which are pivotally mounted upon a bracket member 30, which is screwed fast to the under middle portion of the top plate 6. The releasing bail 28, is provided with a vertical portion 31. A release actuating

dog 32, is pivotally mounted by means of a stud screw 34, upon the vertical portion 31 of the releasing bail 28, and is normally maintained in horizontal position by means of a stop pin 35, which coöperates with the upper wall of an opening 36 formed in about the middle portion of the release actuating dog 32. An escapement rack 37, is operatively connected with a driving shaft 38, upon which is arranged a driving spring (not shown), for propelling the platen carriage 11. The driving shaft 38, is operatively connected with the platen carriage by means of rack and pinion mechanisms (not shown). A holding dog 39 and an escapement dog 40, are pivotally mounted in such manner as to coöperate with the escapement rack to control the movement of the platen carriage for letter spacing. The holding dog 39, is provided with downwardly depending arms 41 and 42, which are adapted to overlie the tail portion 44 of the escapement dog 40. The downwardly depending arm 42 of the holding dog, is provided with an adjustable stop screw 45, which is normally held in contact with the tail portion 44 of the escapement dog, by means of a small coiled spring 46. A similar coiled spring 47, normally maintains the escapement dog 40 in contact with a stop pin 48, thus maintaining the escapement dog 40 out of contact with the escapement rack 37, and the holding dog 39 in contact with the escapement rack 37. The release actuating dog 32, is adapted to abut against the downwardly depending arm 41, of the holding dog 39, in such manner that when the releasing bail 38 is lifted, the nose of the release actuating dog 32 abutting against the downwardly depending arm 41, will cause the holding dog 39 to be swung upon its pivot in such manner as to move the holding dog 39 out of the path of the teeth of the escapement rack 37, thus permitting the carriage to move freely under the propelling force of the driving spring.

The braking bail 29, is provided with a vertical portion 49, to which is pivotally mounted a brake-shoe 50, which normally is maintained against a stop 51 carried upon the vertical portion 49, by means of a small coiled spring 52. The brake-shoe 50, is adapted to coöperate with a brake disk 54, which is fixedly mounted upon the driving shaft 38, when the braking bail is lifted. The tabulator stop carrier 24, terminates at its upper end in a tabulating stop 55 and a releasing cam 56 as shown in Fig. 4. The rear edges of the tabulator stop carriers 24, are provided with locking notches 57, which are adapted to engage a locking plate 58, under the influence of coiled springs 59, when the tabulator stop carriers 24 are lifted by means of the tabulating keys 21. Adjustable stops 60, are adapted to coöper-

ate and be positioned in any of the adjustment notches 61, that are formed in a tabulating bar 62, that is fixedly mounted in the rear of the platen carriage frame 11. The 5 adjustable stops 60, are formed in the shape of a distorted horse-shoe and comprise a stop face 64, a resilient spring portion 65, and a cam actuator 66. The releasing bail 28, is provided on its lower face near its pivot, 10 with an actuating face 67, which is adapted to operate with a pivoted locking dog carrier 68, which carries a locking stop 69, that is adapted to be positioned in the path of an oscillating stop 70, carried by the universal 15 versal bar 10, when the releasing bail is lifted.

The operation of the tabulating device is as follows:—When any one of the tabulating keys 21 are depressed, a particular tabulating stop carrier 24, which is connected with the depressed key 21, is lifted in a vertical direction until the locking notch 67, is thrown into engagement with the locking plate 58. As the tabulator stop carrier 24 is raised, the contact shelves 27, lift the releasing bail 28 and also the braking bail 29. The releasing bail 28, by means of the release actuating dog 32, contacting with the depending arm 41, of the holding dog 39, 25 releases the carriage mechanisms from control of the escapement rack 37. Simultaneously with the releasing of the escapement mechanism, the brake-shoe 60, is forced into position against the brake disk 54, and the high speed of the moving carriage is thus materially reduced. As the tabulator stop carrier 24 is moved upward, the tabulating stop 55 and the releasing cam 56, are moved into the path of the stop face 64 and the 30 cam actuator 66. It will also be noted that as the releasing bail 28 is lifted, the locking stop 69, is moved into the path of the oscillating stop 70, thus effectively locking the printing mechanisms and printing keys 35 when the tabulating mechanism is actuated. Immediately as the carriage mechanisms are permitted to move under the influence of the driving spring, the platen carriage is reciprocated until the cam actuator 66 engages the tabulating stop carrier 24, to be moved outwardly 40 and thus releases the locking notch 57 from engagement with the locking plate 58. However, the stop face 64, engages the tabulating stop 55, so quickly after the releasing of the stop carrier from the locking mechanism, that the carrier has not had sufficient time to entirely remove the tabulating stop from the path of the stop face 64, 45 and thus the main shock of stopping the carriage is transmitted to the tabulating stop 55. Almost immediately as the carriage is stopped, the tabulating stop 55 continues its downward path and drops away 50 from the stop face 64. However, the con-

struction and arrangement of parts are such that the holding dog 39, is moved to reengage the escapement rack 37, before the tabulating stop 55 has entirely left the stop face 64. It will be noted that when the tabulator stop carrier is once sufficiently depressed to release the escapement mechanisms and position the tabulating stop until held or locked in operative position until the carriage has completed its run to bring the tabulating stop and the adjustable stop in contact, that immediately after contact of the tabulating stop and adjustable stop, the tabulating and escapement mechanisms will be returned to normal position, thus permitting the carriage to be again under control of a step-by-step escapement.

Referring more particularly to Figs. 17, 18 and 23, a modified form of the tabulating mechanisms are illustrated, which is particularly adapted for stopping the carriage in a definite columnar position in such manner that upon depressing a column stop the platen carriage may be moved to a position corresponding to a particular predetermined columnar position. The mechanism illustrated in Figs. 17, 18 and 23, is exactly similar to the tabulating mechanism hereinbefore described, with the exception of the lengths of the adjustable stops and the corresponding vertical positions of the tabulating stops and actuating cams, and therefore only these particular parts will be described hereinafter.

Referring particularly to Fig. 23, it will be noted that a column stop 71, is the shorter of the several column stops, and thus when depressed will only rise a sufficient distance to engage the longer adjustable stop 72. A similar relationship of parts exists between the column stops 74, the adjustable stop 75, the column stop 76, the adjustable stop 77, the column stop 78 and the adjustable stop 79. The column stop mechanism is adapted to be substituted and built in in the typewriting machine in place of the ordinary tabulating mechanism, where the typewriting machine is adapted for use for separate column work. Therefore, an adjustable abutment stud 80 is provided, which may be screwed into the machine frame in such manner as to occupy a portion of the space which would normally be filled by tabulating stop carriers. As the major portion of the columnar stop device is identical with the major portion of the tabulating mechanism, further description of the specific elements is thought to be unnecessary.

Referring particularly to Figs. 4, 14, 15 and 16, a changeable or adjustable tabulator scale holder is illustrated, which comprises a small metallic holder 81, that is provided with attaching brackets 82, which are adapted to be attached to the machine frame in such manner as to lie immediately to the

rear of the key caps of the tabulating key levers 21. The metallic holder 81, is adapted to hold a typewritten strip of paper upon which may be designated any particular formula or characters which are to be used in positions on the typewritten sheet, that would be determined by depressing a particular tabulating key lying immediately in front of the character shown on the typewritten strip, thus making a very convenient and easily changed standard formula for use in connection with the tabulating keys, without changing the characters that are designated upon the key caps.

10 Having thus described my invention what I desire to claim is:—

1. In a tabulating mechanism for typewriting machines, the combination of a key lever, a vertically moving stop carrier, said stop carrier being provided with a locking notch, a locking plate, means for causing said locking notch to engage said locking plate when the stop carrier is lifted, a tabulating stop carried by said stop carrier, a releasing cam carried by said stop carrier, a movable carriage, an adjustable stop carried by said movable carriage, and a cam actuator also carried by said movable carriage and adapted to actuate said releasing cam, substantially as described.
2. In a tabulating mechanism for typewriting machines, the combination of a key lever, a stop carrier operatively connected with said key lever, a contact shelf formed on said stop carrier, a releasing bail, a braking bail surrounding said releasing bail, said braking and said releasing bail being adapted to be operated by said contact shelf when said stop carrier is lifted, a tabulating stop on said stop carrier, said stop carrier being formed with a locking notch, a locking plate adapted to engage said locking notch, a releasing cam, a movable carriage, an adjustable stop, and an adjustable cam actuator carried by said movable carriage and adapted to actuate said releasing cam.
3. A tabulating mechanism for typewriting machines comprising a key lever, a stop carrier operatively connected with said key lever, a tabulating stop carried by said stop carrier, a locking plate, said stop carrier being provided with a locking notch, means for causing said locking plate and said locking notch to be interlocked when said stop carrier is lifted, a traveling carriage, an adjustable stop mounted on said traveling carriage, means for causing said locking plate and said locking notch to be disengaged before said adjustable stop contacts with said tabulating stop, an escapement mechanism, means for rendering said escapement mechanism inoperative when said key lever is depressed, a universal bar, and means for locking said universal bar when said escapement mechanism is rendered inoperative.

4. In a tabulating mechanism for typewriting machines, the combination of a key lever, a stop carrier operatively connected with said key lever, an actuating shelf formed upon said stop carrier, an escapement mechanism, a releasing bail, a braking bail, said releasing bail and said braking bail being arranged in the path of said actuating shelf, means operatively connected with said releasing bail in such manner as to cause said escapement mechanism to be inoperative when said releasing bail is lifted, a brake disk, a brake-shoe carried by said braking bail in such manner that said brake-shoe is forced in contact with said brake disk when said braking bail is lifted, substantially as described.

5. A tabulating mechanism for typewriting machines including a tabulator stop, a movable carriage, an adjustable stop mounted upon said movable carriage, means for locking said tabulator stop in operative position, means for unlocking said tabulator stop before said adjustable stop has contacted with said tabulator stop, substantially as described.

6. A tabulating mechanism for typewriting machines including a tabulator stop, a movable carriage, an adjustable stop carried by said movable carriage, means for moving said tabulator stop into the path of said adjustable stop, means for locking said tabulator stop, and means carried by said movable carriage for unlocking said tabulator stop prior to the moment of contact of said tabulator stop and said adjustable stop.

7. A tabulating mechanism for typewriting machines including a tabulator stop, a movable carriage, an adjustable stop carried by said movable carriage, means for positioning said tabulator stop in the path of said adjustable stop, means for locking said tabulator stop when moved into the path of said adjustable stop, a cam member operatively connected with said tabulator stop, and means carried by said movable carriage for co-operation with said cam member to unlock said tabulator stop.

8. A tabulating mechanism for typewriting machines including a tabulator stop, a movable carriage, an adjustable stop adapted to be carried by said movable carriage, means for positioning said tabulator stop in the path of said adjustable stop, means for locking said tabulator stop in the path of said adjustable stop, and means controlled by the movement of said carriage for unlocking said tabulator stop before said adjustable stop and said tabulator stop have met.

9. A tabulating mechanism for typewriting machines including a tabulator stop, a movable carriage, a tabulator stop rack mounted in said movable carriage, an ad-

- justable stop and a cam actuator adapted to be carried by said tabulator stop rack, said adjustable cam actuator being adapted to be seated one notch of said rack in advance of 5 said adjustable stop, a cam member operatively connected with said tabulator stop and arranged in the path of said cam actuator when said tabulator stop is locked in the path of said adjustable stop, an escapement mechanism, and means for rendering said escapement mechanism inoperative during the positioning of said tabulator stop in the path of said adjustable stop.
10. A tabulating mechanism for typewriting machines including a movable carriage, a driving shaft operatively connected with said movable carriage, a brake disk fixedly connected with said driving shaft, a brake-shoe, an escapement mechanism, means for 15 rendering said escapement mechanism inoperative, a tabulator stop, an adjustable stop, means for operating said tabulator stop, means for connecting said brake-shoe with said tabulator stop operating means, and 20 means for connecting said means for rendering said escapement mechanism inoperative with the operating mechanism for the tabulator stop, substantially as described.
11. As a new article of manufacture, an 25 adjustable stop for tabulating mechanism comprising a stop face, a resilient horse-shoe spring member, a cam actuator having its operating face in a plane different from the plane of said stop face, said stop face and said cam actuator being connected by 30 said resilient horse-shoe spring.
12. As a new article of manufacture, an 35
- adjustable stop for tabulating mechanism comprising a stop face, a cam actuator having its operating face in a plane different from the plane of said stop face, and a resilient spring member connecting said stop face and said cam actuator.
13. A tabulator mechanism for typewriting machines including a machine frame, a 40 movable carriage, adjustable stops of different lengths carried by said movable carriage, cam actuators of different lengths carried by said movable carriage, column stops of different lengths mounted in said machine 45 frame, actuating cams of different lengths connected with said column stops, key levers operatively connected with said column stops, said column stops being provided with locking notches, a locking plate, means for 50 causing said locking notches to be interlocked with said locking plate when said column stops are positioned in the path of said adjustable stops, substantially as described.
14. A tabulating mechanism for typewriting machines including a tabulator stop, a 55 movable carriage, an adjustable stop, means for locking said tabulator stop in operative position, and means for unlocking said tabulator stop before said adjustable stop has contacted therewith.

In testimony whereof I affix my signature in presence of two witnesses.

CHARLES SPIRO.
